BOBBIN-CASE CONTROLLING DEVICE

Hermann Pudelko, Bielefeld, Germany, assignor
to Dürkoppwerke Aktiengesellschaft, Bielefeld, GermanyApplication September 24, 1934, Serial No. 745,184
In Germany September 30, 1933

2 Claims. (CL 112—228)

This invention relates to the arrangement of the bobbin-case on sewing machines, especially on button hole sewing machines.

The loop-taker, which as is known serves for guiding the thread, was hitherto arranged in button hole sewing machines in such a manner that the case accommodating the loop-taker was secured on the bed of the machine by two or more screws. If loop-takers were hitherto employed on button hole sewing machines, these were slipped over the loop-taker shaft by means of a holding journal constructed as a sleeve and secured in position by set screws. This construction is, however, open to the great objection that, in the event of it being necessary to remove the loop-taker for the purpose of cleaning, repairing or the like, it is extremely difficult to again fit the loop-taker so that it is in the corresponding position relative to the position of the needle.

As accurate correspondence of the loop-taker position with the needle position is essential for the correct working of a button hole sewing machine. This correct adjusting, a fraction of a millimetre being a determining factor therefor, can, however, be carried out in the known arrangement only by special sewing machine experts, so that great delays occur frequently by the calling in of an expert.

As the known bobbin-case tends to participate in the rotary movement of the loop-taker and must therefore be held tightly, it is constructed so that its two abutments bear alternately at one side against a counterabutment fixed on a rocking escapement yoke or at some other point and on the other side against a counterabutment swinging out periodically, and in this manner is certainly held securely and nevertheless allows the alternate slipping through of the thread loop. As only one counterabutment is capable of swinging outwards, this must travel along a very long path during its swinging out movement, which is only possible owing to a correspondingly high speed, and the bobbin-case likewise has too much play for turning.

As compared with this known construction, the invention consists in arranging a loop-taker on a button hole sewing machine in such a manner that the person operating the machine can remove and replace the loop-taker without any difficulty and without special adjustment, the bobbin-case being provided with a two-armed rocking escapement yoke, the two counterabutments of which need only to travel a short distance and can therefore be moved at a relatively low speed.

This object is attained according to the invention in that the loop-taker engages, by means of a guide in its journal coupled with the loop-taker shaft, with a counterguide on the loop-taker shaft for the purpose of determining the proper adjustment relatively to the position of the needle, and in that a two-armed pivotally mounted holder is provided with abutments which bear alternately against the corresponding counterabutments of the bobbin-case.

An embodiment of the invention is illustrated by way of example in the accompanying drawing in which:—

Fig. 1 shows the controlling device in side elevation, partly in section. 15

Fig. 2 is a front elevation of Fig. 1.

Fig. 3 is a rear elevation of Fig. 1.

Fig. 4 is a longitudinal section of Fig. 1.

A loop-taker shaft 1 which drives a loop-taker 3 designed to accommodate a bobbin case 2, is 20 rotated in known manner from the main driving shaft of the button hole sewing machine. The front end of the loop-taker shaft 1 is, according to the invention, provided with a sleeve 4. A plug 5 inserted in this sleeve 4 has a trans- 25 verse slot 6. The plug 5 is secured against rotation in sleeve 4 by means of a pin 7 or the like. The sleeve 4 and plug 5 may evidently be made in one piece. A journal 9 of the loop-taker has 30 projections 8 which engage in the slot 6 and operatively connect the plug and journal. The journal 9 is secured against shifting in axial direction by means of one or several screws 10.

Instead of the projections engaging in the slot 6 the arrangement may be such, that a pin, 35 bolt or the like extending transversely through the loop-taker shaft constructed as a sleeve, engages in a guide groove in the journal in the sleeve or that the coupling is effected by means of a key and groove.

The bobbin-case 2 is provided with two abutments 11 and 12 which prevent its rotation. Two counterabutments 13 and 14 on a two-armed escapement yoke 15 alternately bear against the two abutments 11 and 12. This escapement yoke 45 15 is fixed on an axle 16 which is actuated from the shaft 1 through the intermediary of a cam 17 and a rocker lever 18. The rocking movement of the lever 18 produced by the cam 17 is transmitted to the escapement yoke which consequently alternately bears now with its counterabutment 13 against the abutment 11 so that the thread loop can slip between the abutments 12 and 14, and then with its counterabutment 14 50 against the abutment 12 of the bobbin-case so 55

that the thread loop can slip through between the abutments 11 and 13.

To enable the play of the bobbin on the space between the abutments to be regulated, one of the abutments, for example the abutment 13, is adjustable.

By the arrangement according to the invention, the loop-taker, if removed, can easily be replaced on the loop-taker shaft in the correct position relative to the needle. All that is necessary is that it be turned once through 180°. This simple operation enables a button hole sewing machine or the loop-taker thereof to be cleaned, repaired or the like without the aid of a special mechanic. Moreover, a smooth and uniform running without considerable wear of the contacting parts is attained, as by the swinging out of the two abutments 13, 14 holding the bobbin-case each of the abutments only moves a short

distance, and consequently only requires to be moved at a slow speed.

I claim:

1. A bobbin case controlling device for button hole and similar sewing machines, comprising in combination with a bobbin case, a two-armed escapement yoke pivotally mounted for rocking movement, a stop on each of the arms of said yoke, a pair of stops on the outer side of said bobbin case for alternately cooperating with the respective stops on said yoke, one of said pair of stops disposed between the center of said bobbin case and the pivotal axis of said yoke, and the other of said pair of stops disposed above the center of the bobbin case.

2. A device as specified in claim 1, in which one of said stops is adjustable.

HERMANN PUDELKO.
